HARNESS MECHANISM

Walter J. Budzyna, East Douglas, and Americo Gouveia, Milford, Mass., assignors to Draper Corporation, Hopedale, Mass., a corporation of Maine

Application June 9, 1951, Serial No. 230,780.

12 Claims. (Cl. 139—89)

1

This invention pertains to improvements in harness top motions, and more especially, to spring top harness mechanisms employing clock type springs such as are utilized for resiliently moving the harness frames to an uppermost position.

It is a general object of the invention to provide a spring top harness mechanism which shall be efficient, long-lived and which shall be completely adjustable throughout a relatively wide range and furthermore, absolutely safe during its operation and when being serviced or adjusted by the loom fixer.

It is a more specific object of the invention to devise a spring top harness mechanism in which a separate spring unit employing a clock type spring shall be provided for each harness frame and said units combined into a simple assembly which is self-contained, but which may, however, be serviced very easily.

It is a further object of the invention to devise improvements in spring top harness mechanisms wherein more or less unlimited range of adjustment is provided for the springs, said adjustment being capable of being effected without disassembling or otherwise disturbing any of the parts of the mechanism except those incidental to effecting adjustment itself.

It is a further object of the invention to devise a spring top harness mechanism which is so designed that the springs may not escape or in any manner endanger the loom operators in the event a spring should break, and further, to provide mechanism of this type which is adapted to have the tension on all of the springs completely and quickly released whenever it is desired to open the mechanism and to affect changes therein during which, in other mechanism of the type, there has always been a considerable amount of danger possible since the springs which are relatively strong have in those instances been left under considerable tension.

Other objects of the invention will become apparent from the following more detailed disclosure.

Spring top harness mechanisms employing clock type springs have been used and an example of one such mechanism which has proven relatively satisfactory is evident in U. S. Patent 2,455,263. While in the top mechanism of that patent and in others, certain adjustments have been provided and have served quite well in most instances, it has not been possible to release tension on any or all springs quickly in the event the mechanism is to be worked on as for replac-

ing a spring, or for effecting adjustments or replacement of any one or more of the individual parts. While each of the springs is separately adjustable, the fact that no great range of adjustment for all the springs has been provided has led to certain disadvantages which are remedied in the present construction.

According to the present invention, each of the springs, one of which is required for each harness frame employed, is a part of a spring unit which includes a hub fixed to a central shaft carried in bearings in a casing member, the spring itself, and a drum which is relatively free on a bearing either on the shaft itself or on the hub which is fixed to the shaft. The spring is attached at one end to the hub and at the other end to the drum. The drum in turn has a harness cord or strap attached thereto which wraps thereabout as the spring pulls the drum in a direction to tighten or to retract the said cord or strap. These cords or straps, of course, run over suitable pulleys or sheaves to their respective harness frames to which they are connected in any convenient manner.

25 The complete assembly of spring units carried on the central shaft as described is adjusted and the springs therein tensioned by rotating the shaft and thus the hubs to which the inner end of the springs are fixed in a direction to wind the springs, by means of a suitable tool which may be applied to a part of the mechanism located outside the casing and fixed to the end of the shaft as it extends from that casing. This latter mentioned part comprises a disk-like, hubbed member which is flattened or otherwise provided for the reception of a wrench or other lever or tool by which the shaft may be rotated to tighten the springs and is also provided with a pawl-like member or members engageable within indentations or against projections formed as a part of, or otherwise provided as an appurtenance to the casing and in alignment with the said pawl-like members. Interengagement between these parts locks the shaft and thus the spring units in any particular adjusted position, but by applying a suitable tool to the adjusting member, releasing the pawl-like members and then rotating the shaft in either one direction or the other, the spring tension may be varied, or if desired, the tension may be completely released as when it is desired to work on the unit and the tension in the springs might be a source of danger at that time.

30 The invention will be described in greater de-

tail by reference to the accompanying figures of drawing wherein:

Fig. 1 is an elevation, part of the casing being broken away, of the mechanism as applied to a loom, only parts appurtenant thereto being illustrated.

Fig. 2 is an elevational view of the opposite side of the mechanism to that seen in Fig. 1.

Fig. 3 is an end view of the device.

Fig. 4 is a section taken at line 4—4, Fig. 2, and illustrating the details of certain parts of the device incidental to a stop for each of the spring units.

Fig. 5 is an exploded view showing one of the spring units and the means by which the spring units may be adjusted and locked in an adjusted position.

Now referring to the figures of drawing, the spring top mechanism is mounted on a pedestal 10 which is supported at the loomside of the loom and comprises among other parts, a casing generally indicated by numeral 11 and which may be cast as a unit or built up from several parts, but which is formed open about more or less of its circumference to be closed by sheet metal covers 12 and 13. These are similar to the covers shown and described in U. S. Patent 2,501,157. A shaft 14 extends centrally through the casing and is relatively free to rotate in bearings, one at either casing side, except as restrained in a manner hereinafter to be described in greater detail. A plurality of spring units generally indicated by the numeral 15 are carried on this shaft and the number of the spring units may vary within limits according to the number of harness frames 16 which are to be controlled or suspended from this top spring mechanism. Each of the frames 16 is suspended upon straps or cords 17, 18, which run over pulleys or sheaves 19 pivoted at 20 on an arch structure which may assume any convenient form, but which preferably employs structural steel members 21 which are attached at one end to the casing 11 by means of suitable bolts or other connecting means 22, and at their other ends to an upright supporting structure (not shown), which may take any convenient form.

Now referring to Fig. 5, as well as the other figures, each of the spring units comprises a hub 23 which is keyed to the shaft 14 by a key 24 which extends along the length of the shaft 14 to serve for all the hubs 23. This hub 23 is in turn flanged as at 26, said flange being under cut for the reception of a bushing 27 rotatable on the smaller diametered part of the said hub and pressed into a corresponding extending portion of the cooperating drum 28. This drum acts as a restraining member for the clock type spring 29 and also as a means to which the extension 30 from the dependent cords or straps 17 and 18 may be connected, for example, by a suitable screw or clamping means 31. The drum 28 has a central hub portion 32 which might rotate on the hub directly, but, as herein illustrated, carries the bushing 27 so that the drum itself is relatively freely rotatable with respect to the shaft and, of course, the hub 23. The outer or flanged part 33 of the drum serves to encase the spring to an extent and that flange is discontinued as at abutment 34, Fig. 1, for the reception of the hooked end 35 of the spring and is also radially offset as at 36 so as to form a stop by means of which movement of the spring unit may be limited, for example, when disconnecting any particular harness frame, or when a cord or some other part of the mechanism fails. It prevents the spring 29

unit from moving, under the tension of its spring, to the fullest extent which might be possible otherwise.

Spring 29 is connected by the inturned or angularly bent part 37 within a notch 38 in the flanged part 33 of hub 23 and the outer coil of the spring is also retained by means of lug 39 cast or otherwise formed as a part of the drum 28. Each of these spring units is assembled and 10 is keyed to the shaft 14 so that by rotating the shaft 14 in the appropriate direction, tension is imposed on the clock type spring 29, the adjustment of these springs being dependent upon other factors including the type of harness frames, the speed of operation of the loom, and several other factors.

It has been found that each of the spring units is substantially like the others and that adjustment of them all simultaneously serves best to 20 tension the springs and therefore, as will presently be described, an adjustment is provided by means of which the shaft 14 may be turned throughout any desired angular extent and be held at whatever adjusted position serves most 25 advantageously for the particular installation at hand. The adjustment is possible of being effected without removing any parts and without obtaining access to the interior of the casing. Adjustment and locking of the parts in position 30 are effected through interengaging means part of which is a functionally integral part of the casing and another part of which is mounted on and movable with the shaft on which the spring units are affixed and which may comprise a disk-like member generally indicated by numeral 40 and which is flanged as at 41 and has a projecting hub portion 42 flattened at opposite sides for reception of a wrench or other suitable tool to be employed as a lever in turning the shaft 14 or holding it in any position incidental to the adjustment thereof. It is thus possible to effect 40 the tensioning of the springs without involving the loom operator or fixer in any possibility of being struck by a broken spring or of getting a finger caught in the mechanism, and, in fact, it is not at all necessary to disturb any of the individual spring units during the adjustment except to tension them by rotating the shaft 14. The parts are held in an adjusted position by the 45 cooperating action of certain pawl-like members 43 which engage teeth 44, or by any similar and equivalent means such as spring pressed plungers which might cooperate with openings or other indentations taking the place of the teeth 44. In 50 fact, it is the pawl-like projection or projections 43 which engage within the indentations between the teeth 44 and the actual form which these parts take is not important so long as they comprise a means for maintaining relatively fine settings and for maintaining the position of the 55 parts very positively.

The teeth 44 may be cast integrally with the casing 10, or be formed on a separate element bolted or otherwise attached thereto. The pawl-like members 43 are a part of the plungers 45 which are retained within suitable openings in the part 40 and which are spring pressed by means of a spring 46 so that the pawl is normally maintained in engagement with the teeth 44. A button or other projecting means 47 serves to withdraw the pawls from the teeth whenever it is desired to change the position of the parts. While one pawl 43 may suffice, it is preferred that two such pawls be employed and that they be 60 spaced so that one is always at the half-tooth

position when the other is engaged with a particular tooth. This makes possible an angular adjustment equivalent to one-half the angle between teeth and therefore makes it unnecessary to have extremely small teeth.

The buttons or washers 41 are adapted to be engaged by a wedged tool such as a screw-driver, and by prying up one pawl at a time and operating on them alternately, the tension may be released slowly. If a major adjustment is to be made it will probably be more expeditious to pry out both pawls after applying a wrench to the member 42 and to turn the shaft by the wrench. In any event, the shaft which is shouldered at the end opposite that at which adjustment is made, is clamped by a nut 48. Before making any adjustment that nut is loosened, and when the adjustment is completed, it is tightened. When adjusting the parts so as to tighten the springs it is only necessary to apply the wrench or other tool and to turn the shaft in the appropriate direction. The pawls 43 slip past the teeth and make engagement automatically.

As shown in Figs. 1-4, a stop in the form of a rod 49 extends across, but angularly of the casing 10 at the lower part thereof and in a position to be engaged by the projections 36 on each of the drums 28. This rod has reduced ends, the end 50 of which is spring pressed, which enter within receiving apertures in the lugs 51 and 52 which are preferably cast integrally with the casing. The angular position of the stop bar or rod provides for spacing each of the projections 36 a very short distance from the bar so that if a cord or strap breaks, the movement of the unit under the quickly released and relatively great spring force acting thereon will move the drum 28 only throughout a very small distance before the extension 36 engages the stop member 49. In actual practice these are separated about one-half inch when the mechanism is in the position such that its harness frame is uppermost. Since the harness frames move throughout different distances decreasing from the front to the back harness, the angularity of the stop 49 is of such nature as to take care of the difference in movement for each of the spring units.

A provision is made for lubricating the bearings between the bushings and the hubs 23. The shaft 14 is drilled along its length to a point past the last bushing at the end opposite nut 48. A fitting 53 serves to permit lubrication by a pressure gun and a series of radial holes 54 through both shaft and hub 23 and registering with the central hole in the shaft lead the lubricant to the proper surfaces.

In this specification and claims the term "predetermined tension" refers to that tension by which the harness cords affect the harnesses as determined for a particular loom condition, and the spring tension for effecting that harness cord tension. The drums 28 have been spoken of as being rotatable on or relatively to the shaft. They do rotate on the hubs on the shaft, but it is obvious that they could be pivoted on the shaft and the hubs then shortened but still keyed to the shaft. The pawl members may be pivoted or movable in any other fashion so long as they function to engage the teeth which cooperate with them, and may be withdrawn when required.

While one embodiment of the invention has been disclosed, it is to be understood that the inventive concept may be carried out in a number of ways. The invention is, therefore, not to be limited to the precise details described, but

is intended to embrace all variations and modifications thereof falling within the spirit of the invention and the scope of the claims.

We claim:

5. 1. A spring top harness mechanism for looms comprising a supporting casing, a shaft borne within said casing and a plurality of clock spring units carried on said shaft and within said casing, each said unit including a hub fixed to the shaft, a drum to which a harness cord is attached said drum being rotatable relative to said shaft and a clock spring having one end fixed to said hub and the other end fixed to the drum, and means comprising complementary, interengaging means a plurality of which form a part of said casing and at least one of which is carried by said shaft for releasably locking said spring units in a predetermined, tensioned relationship.
10. 2. A spring top harness mechanism for looms comprising a supporting casing, a shaft borne within said casing and a plurality of clock spring units carried on said shaft and within said casing, each said unit including a hub fixed to the shaft, a drum to which a harness cord is attached said drum being rotatable relative to said shaft and a clock spring having one end fixed to said hub and the other end fixed to the drum, and means for rotating said shaft to tension the springs and for retaining the springs in tensioned relationship comprising a member fixed to said shaft externally of the casing, said member having surfaces adapted to receive an instrument for applying torque to the shaft and means for releasably locking said spring units in a desired, tensioned relationship which comprises interengaging means part of which is a functionally integral part of the casing and another part of which is mounted on and movable with the shaft on which the spring units are affixed.
15. 3. A spring top harness mechanism for looms comprising a supporting casing, a shaft borne within said casing and a plurality of clock spring units carried on said shaft and within said casing, each said unit including a hub fixed to the shaft, a drum to which a harness cord is attached said drum being rotatable relative to said shaft and a clock spring having one end fixed to said hub and the other end fixed to the drum, a series of teeth forming a part of the casing and means fixed to the shaft externally of the casing for cooperating therewith and including a disk-like, hubbed member concentric with said series of teeth and releasable pawl means carried by said member and engageable with said teeth for retaining the spring units in an adjusted position.
20. 4. In a spring top harness mechanism for looms a casing, a shaft extending through and borne in said casing, means for retaining said shaft in an angularly adjusted position and a plurality of spring units carried by said shaft within the casing, each said unit comprising a flanged hub fixed to the shaft, a drum to which a harness cord is attached said drum being rotatably carried upon the said flanged hub and a clock type spring encased within said drum and having one end attached to the drum and the other end attached to the flange of said hub.
25. 5. In a spring top harness mechanism for looms a casing, a shaft extending through and borne in said casing, means for retaining said shaft in an angularly adjusted position and a plurality of spring units carried by said shaft within the casing, each said unit comprising a hub keyed to the shaft, a drum to which a harness cord is attached said drum being rotatably

carried on said hub, a notch in said hub and an anchoring abutment forming a part of said drum, and a clock type spring confined within said drum and having one of its ends held in said notch and the other connected to said anchoring abutment.

6. In a spring top harness mechanism for
looms a casing, a shaft extending through and
borne in said casing, means for retaining said
shaft in an angularly adjusted position and a 10
plurality of spring units carried by said shaft
within the casing, each said unit comprising a
hub keyed to the shaft, a drum to which a
harness cord is attached said drum being rotatably
carried on said hub, a notch in said hub and
an anchoring abutment forming a part of said
drum, and a clock type spring confined within
said drum and having one of its ends held in
said notch and the other connected to said
anchoring abutment and means for stopping
movement of said spring units which comprises
a projection on each drum and a cooperating
member extending laterally of said casing and
in the pathway of said projections.

7. Mechanism as defined in claim 6 wherein said cooperating member comprises a bar extending across said casing and inclined to the axis of said shaft by an amount substantially sufficient for compensating for the normal difference in movement of said units in accordance with the difference in amplitude of movement of their respective harness frames.

8. For use in a spring top harness mechanism for looms a spring unit comprising a hub adapted to be fixed to a retaining shaft, said hub having an external bearing portion and a spring attaching portion, a drum having a hub borne upon the bearing portion of said first mentioned hub and an abutment for attachment of a spring, and a clock type spring having one end secured to said spring attaching portion of the first mentioned hub and its other end secured to said abutment.

ment.
9. For use in a spring top harness mechanism for looms a spring unit comprising a hub adapted to be fixed to a retaining shaft, said hub having an external bearing portion and a notched flange,

a spring retaining drum having a central hub borne upon the bearing portion of said first mentioned hub, an external spring restraining flange, an abutment formed by the interruption of the external spring restraining flange of said drum and a radially offset projection of said flange, and a clock type spring one end of which is received in said notched flange of the first mentioned hub and the other end of which is hooked about said abutment.

about said abutment.

10. A spring top harness mechanism for looms comprising a casing, a centrally disposed shaft extending through said casing, a plurality of spring units operatively affixed to said shaft and being provided for attachment of harness cords extending therefrom to their respective harness frames, and means for adjustably retaining said shaft in an angularly adjusted position comprising a disk-like member fixed to said shaft externally of the casing, at least one spring urged pawl member carried by said disk-like member and having provision for manual retraction and complementary, spaced pawl engaging indentations formed in said casing and aligned for interaction with said pawl member.

11. A loom claim 10 wherein

25 teraction with said pawl member.
11. Mechanism as defined in claim 10 wherein
said disk-like member is also provided with a hub
having flattened sides for reception of a hold-
ing tool.

30 12. Mechanism as defined in claim 10 wherein
said pawl-like member is spring pressed axially
of the shaft and said indentations are formed as
spaces between teeth circumferentially disposed
about the axis of said shaft.
